UNITED STATES PATENT OFFICE.

CHARLES E. KOESTER, JR., OF KOESTER, MISSOURI, ASSIGNOR OF ONE-HALF TO
EDWIN A. DARROW, OF ST. LOUIS, MISSOURI.

MOP HOLDER.

Application filed April 29, 1921, Serial No. 465,441. Renewed April 21, 1923.

To all whom it may concern:

Be it known that I, CHARLES E. KOESTER, Jr., a citizen of the United States, residing at Koester, in the county of St. Francois and 5 State of Missouri, have invented new and useful Improvements in Mop Holders, of which the following is a specification.

This invention relates to improvements in combined brush and mop holders and carpet 10 stretching devices.

The type of device upon which the present invention is an improvement includes a threaded ferrule upon which is mounted a ring which is connected to a gripping member. The objection to this structure is that during the use of the device, the brush or mop to which it is secured, becomes loose, due to the fact that at times one end of the gripping member guide bar, which forms a 15 part of the device, will contact with some object and cause the threaded ring to "back up" on the ferrule and thus loosen the hold of the gripping member.

The present invention aims to overcome 20 this and other objections, by forming the guide bar through which the gripping member passes, rigid with the ferrule and so prevent relative movement. Contact of the guide bar with an object will then not affect 25 the ring or loosen the member.

Another object is the provision of a novel 30 structure for this purpose, which is cheaply constructed and readily assembled.

With the above and other objects in view, 35 the invention further includes the following novel features and details of construction, to be hereinafter more fully described, illustrated in the accompanying drawings and pointed out in the appended claims.

40 In the drawings:—

Figure 1 is a plan view of a combined brush and mop holder and carpet stretching device, embodying the present invention.

Figure 2 is an end view looking at the end 45 of the holder which receives the handle.

Figure 3 is a side view of the holder.

Figure 4 is a central longitudinal sectional view.

Figure 5 is a detail perspective view of the 50 follower ring which carries the gripping member.

Figure 5^a is a plan view of the follower ring.

Figure 6 is a similar view of one of the sections of which the adjusting nut is 55 formed.

Figure 7 is a detail elevation of the guide bar for the gripping member.

Referring in detail to the drawings, wherein like characters of reference denote corresponding parts, the reference character 10 indicates an externally threaded ferrule which receives one end of a wooden handle 11 and which carries at its opposite end a transversely arranged guide bar 12. This 60 guide bar is provided with longitudinal slots 13 for the passage of a wire gripping member 14 and is further provided with a hook 15 and teeth 16, the latter extending from one side edge of the bar 12. The structure of 65 the above mentioned elements is old and the above mentioned elements is old and form a part of a combined brush and mop holder and carpet stretching device now on the market.

In order to permit of adjustment of the 70 wire gripping member, the device now in use provides for relative movement between the ferrule and the gripping member of the guide bar. As previously stated however, this is objectionable in that such relative 75 movement permits of a loosening of the gripping member upon the brush or mop. To overcome this, the guide bar 12 of the present invention is rigid with the ferrule 80 10 and may be formed integral therewith 85 or secured thereto in any desired manner. One means of securing the guide bar to the ferrule is by providing a reduced squared lug which projects from the end of the ferrule as indicated at 17 and inserting and 90 riveting this lug within a squared opening 18 formed in the guide bar 12. The gripping member 14 has its arms extending through the slots 13 of the guide bar 12 and the ends of these arms are connected to 95 oppositely extending apertured ears 19 which are carried by a follower ring 20. The ring 20 is mounted upon the ferrule 10 and is of a diameter to permit of free movement of the longitudinal ferrule.

Mounted upon the ferrule is an adjusting nut 21, which is formed of a pair of com-

plemental sections, each of which comprise a semi-circular portion 22 which is provided with an interior spirally arranged bead 23, so that when the sections of the nut are assembled a thread is formed for engagement with the threads of the ferrule 10. The sections of the nut are also provided with oppositely extending projections 24, one of which has secured thereto a lug or rivet 25 which is adapted to be secured in an opening 26 provided in the projection of the other section of the nut, while the opposite projections 24 have registering openings 27 therein for the reception of a rivet or other fastening device. The sections are thus secured together to provide oppositely extending wings, by means of which the nut may be manipulated. The nut is further provided with an interiorly arranged annular groove 28 which receives oppositely extending lugs or projections 29, carried by the follower ring 20, so that the said ring is swiveled to the nut. The ring, nut and guide bar may be provided in various places with depressions for the purpose of lightening the structure.

In the present invention, the member 14 is passed through the slots 13 of the guide bar 12 in the usual manner and the ends of the member remains so secured within the apertured ears 27 of the follower ring and the nut sections so riveted together with the flanges or projections 29 engaged in the annular groove 28.

By rotating the adjusting nut, the gripping member may be moved to either tighten or loosen its engagement with the proper brush and as the guide bar 12 is rigid with the ferrule, a blow upon the former will not effect the adjustment of the gripping member. The wings of the adjusting nut are within the ends of the bar 12, so that liability of contact of these wings with an article is prevented. After once being adjusted, the parts will remain in position until purposely removed.

The invention is susceptible of various changes in its form, proportions and minor details of construction and the right is here-

in reserved to make such changes as properly fall within the scope of the appended claims.

Having described the invention what is claimed is:—

1. A mop holder comprising a handle-receiving ferrule, a guide bar at one end of the ferrule, a gripping member slideable in guide openings formed in said guide bar to provide a clamp, a grooved nut threadedly engaging the said ferrule, and a ring loosely encircling the said ferrule and having outstanding projections, certain of which are connected to the said gripping member and certain others engaged in the groove in the said nut whereby the ring is swiveled to the latter.

2. A mop holder comprising an exteriorly threaded ferrule, adapted to receive a handle, a guide bar at one end thereof, a gripping member slideable in guide openings formed in the guide bar to provide a clamp, a follower ring loosely encircling the said ferrule and connected to the said gripping member, said ring having oppositely projecting lugs, and an adjusting nut threadedly engaging the said ferrule and having an interiorly arranged annular groove which receives the lugs of the said ring whereby the latter is swiveled to the nut.

3. A mop holder comprising a handle-receiving ferrule having a guide bar at the lower end, a ring adjustable longitudinally on the said ferrule and presenting opposite sets of radially disposed projections adjacent its upper and lower edges, a mop-gripping member slideable in guide openings formed in said guide bar to provide a clamp and attached to the lower projections of the said ring whereby it is adjustable with the latter, and a nut threadedly engaging the said ferrule and having an interiorly grooved portion engageable over the said ring to accommodate the said upper projections of the latter, whereby the ring and nut are swiveled together for simultaneous adjustment.

In testimony whereof I affix my signature.

CHARLES E. KOESTER, JR.
